UNITED STATES PATENT OFFICE

THOMAS J. STURTEVANT, OF WELLESLEY, MASSACHUSETTS, ASSIGNOR TO STURTEVANT MILL COMPANY, OF BOSTON, MASSACHUSETTS, A CORPORATION OF MASSACHUSETTS

AIR SEPARATOR

Application filed February 1, 1930. Serial No. 425,100.

The invention to be hereinafter described relates to air separators for grading materials, and is embodied in a separator of the type in which the classification is accomplished by an air current moving upward in a separating chamber and downward in a settling chamber. The air current is induced by a fan and caused to whirl and circulate through the chambers. The materials to be graded are fed through a hopper into the separating chamber and are received by a rotary distributor which throws the materials out across the rising air current under the influence of centrifugal force. The lighter particles or fines are carried upward by the air current out of the separating chamber over into the settling chamber where they gravitate downward and are delivered therefrom, while the heavier particles or tailings gravitate downward through the rising air current in the separating chamber and are delivered therefrom.

Heavier particles gravitating down from the separating zone in the separating chamber, carry with them some of the fines which adhere thereto, and this is especially pronounced when sticky materials are being classified. As a consequence, these fines have been carried on down with the tailings out of the separating chamber, whereas if they could be dislodged therefrom, they would be carried upward by the whirling rising air current over into the settling chamber, and the efficiency of separation would be materially increased.

Heretofore, a series of short vanes has been provided beneath the lower conical end of the separating chamber, and the air passed from the settling chamber through the spaces between the vanes up into the separating chamber. The air whirling in the latter tended to cause the heavier particles gravitating down from the separating chamber, to fly out toward the vanes under the influence of centrifugal force, but the air curling up around the lower edge of the separating chamber and the velocity of the air entering therein practically prevented the tailings from reaching the vanes.

A purpose of the present invention is to

dislodge from the coarser particles fines adhering thereto, and also to break up the coarser particles into finer particles to some extent. To accomplish this, a main portion of the wall of the separating chamber is formed of elongated vanes having narrow spaces between them through which the air passes laterally into the separating chamber. The total opening between the vanes may be as great as the total opening provided by the short vanes in the former separator, but the velocity of the air passing between the vanes will be very much less, and will be sufficiently low to allow the heavier particles whirling in the separating chamber to be thrown outward under the influence of centrifugal force against the inner surfaces of the vanes. The length of these vanes is such that the heavier particles will whirl in a spiral path of multiple rather flat convolutions, and repeatedly batter and rattle against the vanes, causing the fines adhering to the tailings to be dislodged therefrom and causing heavier particles to be broken up with mechanical action. The smaller particles thus freed are winnowed from the heavier particles and carried up by the rising air current in the separating chamber and over into the settling chamber, thereby materially increasing the efficiency of the separator.

Another purpose of the invention is to provide means for regulating the classification taking place in the upper zone of the separating chamber. To accomplish this baffles are provided and are adjustable to vary the separating effect of the air whirling and rising in the separating chamber, so that coarser or finer particles may be carried over into the settling chamber as required. Also these baffles may be adjusted to positions where they are inoperative in affecting the classification if desired.

The character of the invention may be best understood by reference to the following description of one good form thereof shown in the accompanying drawings, wherein:

Fig. 1 is a view, in vertical longitudinal section, through a separator embodying the invention;

Fig. 2 is a view, in horizontal section, taken on line 2—2 of Fig. 1;

Fig. 3 on an enlarged scale is a view, in sectional detail, of some of the vanes;

Fig. 4 is a perspective view of one of the vanes;

Fig. 5 is a view, in horizontal section, through the separator showing the disposition of the baffles; and

Fig. 6 on an enlarged scale is a side view of one of the baffles and its mounting.

Referring to the drawings, the separator shown therein as one good form of the invention, comprises an outer casing 1 (Fig. 1) consisting of a drum 3 having a head 5 at its upper end, and a cone 7 depending from the lower end thereof terminating in a discharge spout 9. This outer casing is provided with brackets 11 adapted to rest upon and be secured to suitable supports.

Within and spaced from the outer casing is an inner casing comprising an inner cylindrical shell 13 having a head 15 at the upper end thereof with a central outlet opening 17 therein, said shell being supported by brackets 19 secured to the outer and inner casings. The outlet opening may be provided with a valve for varying its effective opening comprising a series of overlapping plates 21 connected to rods 23 which project outward through the drum 3, and are accessible for adjustment externally of the separator. This valve may be the same as that disclosed in Letters Patent of the United States No. 1,615,558, granted to me January 25, 1927, and therefore further showing and description thereof are unnecessary herein.

The inner casing also includes a conical shell 25 having its upper end spaced a substantial distance beneath the upper shell 13. The lower end of this conical shell communicates with a spout 27 which passes laterally through an opening in the cone 7, referred to. The conical shell is supported on the cone 7 by webs 29 secured to angle bars 31 secured to said cone. In the inner casing is the separating chamber 33, and between the inner and outer casings is the settling chamber 35.

The lower and a main portion of the wall 50 of the separating chamber is formed of a series of spaced overlapping elongated vanes 37 which are flush with and extend from the lower edge of the upper shell 13 down into the lower conical shell 25, and in the present instance the assembly is of frusto-conical form. The vanes are principally above the lower end of the separating chamber. They are carried by the upper shell, and to accomplish this have flanges 39 (Figs. 3 and 4) at the upper ends thereof pivotally connected by bolts 41 to a collar 43 projecting outward from the lower edge of the upper shell. The form of the vane flanges 39 is such that escape of materials from the separating chamber past

the collar into the settling chamber is prevented.

To conduct materials into the separator, a suitable hopper (not shown) may be connected to the intake neck 45 (Fig. 1) which leads to a conical hopper 47 secured to the outer casing head. At the top of the separator are channels 49 supporting a housing 51 containing bearings in which is journaled a vertical shaft 53 rotated by a bevel gear 55 fast thereon meshing with a bevel gear 57 on a horizontal shaft 59 journaled in a bearing carried by the housing and an outer bearing 61, said shaft being provided with a pulley 63 which may be driven from any suitable source of power.

The shaft 53 projects down through and beyond the hopper 47 into the separating chamber, and carries a rotary distributor 65. Projecting up from the distributor are posts 67 carrying a baffle plate 69. The fan for causing the air to circulate and whirl through the separating and settling chambers comprises a conical shell hub 71 having a flange mounted on and secured to the posts 67. This shell hub encircles and is spaced from the hopper 47, and projects up through the opening 17 in the inner casing head. Secured to the upper end of the hub are plates 73 carrying fan blades 75.

To vary the whirl and separating effect in the upper zone of the separating chamber, a series of baffles 77 (Figs. 1, 5 and 6) may be provided, in the present instance of triangular form and located at the juncture of the shell 13 with the head 15 of the inner casing, and preferably these baffles extend substantially to the edge of the head opening. Each of these baffles, in the present instance, is bolted to the flattened end of a shaft 79 which projects through a tubular bearing extending between the shell 13 and drum 3, and at the outer end of the shaft is a handle 81 accessible externally of the separator. The construction is such that the baffles may be adjusted to different positions of angular adjustment forwardly and backwardly from vertical positions. Also, they may be adjusted to inoperative positions, where they lie parallel to the under surface of the inner casing head. They may be secured in their different positions by set screws 83 on an external bearing carried by the drum 3. While in the present embodiment the baffles 77 are mounted on horizontal shafts, it will be understood that they might be mounted on vertical shafts and adjusted on vertical axes with equal effect.

In operation, the material to be graded is fed through the neck 45 into the hopper 47, and thence to the rotary distributor 65, which throws the material outward under the influence of centrifugal force. The fan causes the air to circulate and whirl in a path upward through the separating chamber,

through the outlet opening in the head thereof, through the fan chamber, down in the settling chamber through the inlet opening afforded by the spaces between the vanes and

5 back into the separating chamber. The lighter particles of material will be carried upward by the air in the separating chamber over into the settling chamber, and be delivered through the spout 9. The heavier

10 particles will gravitate downward in the separating chamber and be delivered through the spout 27.

15 The vanes 37 constitute a main portion of the wall of the separating chamber and extend from the upper separating zone down to the lower end of the separating chamber. The upper ends of the vanes are flush with the shell 13 and the lower ends of the vanes are spaced from the conical shell 25 slightly

20 to allow adjustment of the vanes. Therefore these shells and vanes form a substantially continuous wall for the inner casing.

25 The velocity of the air passing from the settling chamber laterally between the vanes into the separating chamber will be sufficiently low to allow the heavier particles gravitating down and whirling in the zone bounded by the vanes, to be thrown against the inner surfaces of the vanes under the influence of

30 centrifugal force. Their spiral whirl is in multiple fairly flat convolutions in this zone, so that they will be carried around repeatedly and batter and rattle against the inner surfaces of the vanes. Their impact will cause fines adhering to the tailings to be dislodged therefrom and cause the tailings to be broken up more or less, so that the fines may be winnowed out and carried on up with the whirling rising air current out of the separating

35 chamber over into the settling chamber. As a result, fines which otherwise would pass out of the separating chamber with the tailings, are delivered into the settling chamber, thereby increasing the percentage of fines

40 separated and hence increasing the efficiency of the separator. The vanes may be adjusted on their carrying bolts to vary their spacing as required.

45 The baffles 77 are desirable as providing regulation of the classification in the main classification zone within the shell 13. They may be adjusted to vary the effect of the whirling rising air current in this zone, so that particles of greater or less degree of fineness may be separated and carried over into the settling chamber. The handles of the shafts carrying the baffles are located externally of the outer casing where they are conveniently accessible.

50 By my invention an improved separator is provided which efficiently dislodges from the tailings fines adhering thereto with mechanical action and permits the air current

55 to winnow out these fines and include them

with the main stream of fines delivered to the settling chamber.

It will be understood that the invention is not limited to the specific embodiment shown, and that various deviations may be made therefrom without departing from the spirit and scope of the appended claims.

What is claimed is:

1. An air separator for grading materials comprising, in combination, an outer casing, 75 an inner casing, a separating chamber in the inner casing, a settling chamber between said casings, said inner casing having a head with an outlet therein, means for causing air to circulate and whirl through said chambers and outlet, and a series of baffles in the separating chamber at the juncture of the inner casing with its head and extending substantially to the outlet opening in the head, said baffles being adapted to vary the separation 80 effect of the air whirling and rising in the separating chamber.

2. An air separator for grading materials comprising, in combination, separating and settling chambers having inlet and outlet 90 openings between them, means to cause air to circulate and whirl through said chambers and openings and move up in the separating chamber and down in the settling chamber, and a series of relatively movable overlapping spaced vanes at the inlet opening arranged to form a frusto conical wall which is a substantial portion of the separating chamber wall, said vanes having sufficient 95 spacing and length so that the bulk of the whirling heavier particles within the separating chamber will batter against the vanes and dislodge fines therefrom to be carried up by the rising air in the separating chamber.

3. An air separator of the type comprising separating and settling chambers having inlet and outlet openings between them, means to cause air to circulate through said chambers and openings and move up in the separating chamber and down in the settling chamber, said separating chamber being characterized by an upper cylindrical portion and a lower frusto conical portion, the 110 wall of said upper cylindrical portion being impenetrable and the wall of said lower conical portion being formed by a circular series of spaced overlapping vanes, the openings therebetween forming said inlet opening from the settling chamber to the separating 115 chamber.

4. The invention described by claim 3 in which the said vanes are adjustable to vary the area of said inlet opening.

5. An air separator of the type comprising a cylindrical casing, a second cylindrical casing of less length suspended within said first casing, said inner casing having a depending frusto conical wall having its lower end substantially in the 125 130

plane of the lower edge of said first casing, and two nested cones below and constructed to enclose the bottom openings of said outer casing and frusto conical wall of said inner casing, said frusto conical wall of the inner casing being formed wholly of a series of spaced, overlapping vanes each extending from top to bottom thereof.

6. The invention described by claim 5 in which the said vanes are relatively adjustable to vary the lap and consequently the width of the spaces between them.

7. In an air separator of the type having a circular, walled separating chamber and an outer annular settling chamber with means for causing air to whirl within the separating chamber, pass out through its top, down through the settling chamber and back through substantially the lower half of the height of the wall of the separating chamber, said lower half of said separating chamber wall being frusto conical in shape and composed of a series of spaced, overlapping upright vanes each of which is pivoted for an opening movement into the separating chamber, the major portion of said vanes lying inside the separating chamber when arranged in their opened relation.

8. An air separator comprising a cylindrical covered casing, a smaller cylindrical covered casing within said first casing, said inner casing having a centralized outlet in its cover and an inlet at its bottom for establishing communication between said two casings, means for causing air to whirl and circulate up in the inner casing, through said outlet, down between the two casings and through said inlet, and a series of baffles located in the upper corner of said inner casing outside of said outlet opening.

9. The invention described by claim 8 in which each of said baffles consists of a plate extending radially into said casing.

10. The invention described by claim 8 in which said baffles consist of movable partitions projecting into the casing from its outer wall.

11. The invention described by claim 8 in which said baffles consists of plates, in combination with means for setting said plates at varying inclinations to the path of movement of the whirling air currents.

12. The invention described by claim 8 in which said baffles consist of swivelled plates, said swivels extending outward to the outside of the outer casing for external control of the angular position of said baffles.

THOMAS J. STURTEVANT.
